DISPENSING CONTAINER FOR A CAKE OF FABRIC SOFTENER AND ANTI-STATIC AGENT FOR USE IN AUTOMATIC CLOTHES DRYERS

John S. Levey, 4059 Mariner Circle,
Westlake Village, Calif. 91361

Filed July 15, 1974, Ser. No. 488,444

Term of patent 14 years

Int. Cl. D23—04

U.S. Cl. D23—150

FIG. 1 is a front elevational view of a dispensing container for a cake of fabric softener and anti-static agent for use in automatic clothes dryers showing my new design;

FIG. 2 is a rear elevational view thereof;
FIG. 3 is a side elevational view thereof.

I claim:

The ornamental design for a dispensing container for a cake of fabric softener and anti-static agent for use in automatic clothes dryers, as shown and described.
